UNITED STATES PATENT OFFICE.

ERICK J. SWEDLUND, OF WILLISTON, NORTH DAKOTA.

SEPARABLE CUFF BUTTON.

Application filed April 25, 1921. Serial No. 464,296.

To all whom it may concern:

Be it known that I, ERICK J. SWEDLUND, a citizen of the United States, residing at Williston, in the county of Williams and 5 State of North Dakota, have invented certain new and useful Improvements in Separable Cuff Buttons, of which the following is a specification.

This invention relates to certain new and 10 useful improvements in separable cuff buttons, and it has for its objects among others to provide a simple, efficient, improved separable cuff button, composed of few parts, those capable of manufacture at small cost 15 and readily assembled, yet efficient and reliable in use.

The parts are made of sheet metal, stamped out, and thus capable of manufacture at minimum cost, and the parts are so 20 constructed and assembled that the button is easily operated, the parts being separated by movement in the direction in which they are moved to close the same.

Other objects and advantages of the invention will hereinafter appear, and the 25 novel features thereof will be specifically defined by the appended claims.

The invention is clearly illustrated in the accompanying drawings, which, with the 30 numerals of reference marked thereon, form a part of this specification, and in which—

Figure 1 is a view of the button with the 35 parts in closed position, one portion being in section and the other in elevation.

Figure 2 is a similar view showing the 40 parts in the position they assume when pressure is applied to separate the parts.

Figure 3 is a cross section as on the line 3—3 of Figure 1, looking in the direction 45 of the arrows.

Figure 4 is a view of the tubular member or sleeve and front plate of the body portion of the button removed, parts being in elevation and the front plate in section.

45 Like numerals of reference indicate like parts throughout the several views.

The body portion of the button is composed of a front member 1, with sleeve 2, the member 3 with a sleeve 4, which fits 50 within the sleeve 2, as seen in Figures 2 and 1, its inner end being beaded or out-turned as seen to hold the two parts together, the bead or out-turned portion being formed in any suitable manner as at 5, and a back 55 plate 6, which is held in place by bending the member 3 over the edge thereof as seen at

7. This completes the button or body portion of the button.

The other, or locking portion of the button 8, is similar to that just described, comprising a member 9, a post 10 and a member 11, constructed substantially in the same manner as the body portion just described, and carries a stud 12 with a head 13, the end of which is shown as tapered at 14, there 60 being a shoulder 15 intermediate the ends of the stud as seen in Figures 1 and 2.

16 is a spring interposed between this tapered end of the head and the member 1 as seen in Figures 1 and 2 to normally tend 70 to force the parts away from each other to hold them in locked position. This spring, however, may sometimes be omitted.

The sleeve 4 is formed with slanting 75 grooves or notches 17, as seen best in Figure 4, to give a wedging engagement to the spring 18, which is located within the hollow space 19 in the head of the button proper, as seen in Figures 1 and 2. The form of this spring is clearly shown in Figure 3. 80

20 is a ring loosely slidable on the stud 12 as seen in Figures 1 and 2. This serves as the key to unlock the two parts of the button.

As seen in Figure 1 the parts are in 85 locked position. In order to separate the parts all that is necessary is to simply press the two parts of the button together or toward each other, in the same manner as in locking them, only pressing a little harder. 90 This will force the sliding sleeve or ring 20 against the spring 18 which will yield and allow the ring 20 to slide under it, as seen in Figure 2, so that the plunger or stud 12 can be withdrawn. 95

As seen in Figures 1 and 2 the spring 18 has flat contract portions 21 to allow it to slide over the dividing line between the ring 20 and the head 13. It will be readily understood that as the ring 100 is forced beneath the flat portions of the spring the latter will be raised or moved outward so that it does not interfere with the outward movement of the stud with its head, the shoulder 15 not interfering with the endwise movement of the stud.

Modifications in detail may be resorted to without departing from the spirit of the invention or sacrificing any of its advantages. 110

What is claimed as new is:—

1. A button comprising two separable

parts each adapted to engage with a button hole in a garment, one of said parts being provided with a locking sleeve and with a locking member, laterally tensioned, and the other part carrying a stud engagable by said locking member, and a manually operated member adapted to engage and move said locking member to release position.

2. A button comprising two separable parts each adapted to engage with a button hole in a garment, one of said parts being provided with a locking sleeve and with a locking member, laterally tensioned, and the other part carrying a stud engageable by said locking member, and a manually operated slideable member adapted to engage and move said locking member to release position.

3. A separable button comprising two separable self-contained parts, movable in the same direction for locking and unlocking, and a spring within the one part co-operable with means on the other part for locking purposes laterally tensioned by the inward movement only of the other part.

4. A separable cuff button composed of two self-contained parts, a stud carried by the one part, a laterally-tensioned spring carried by the other part, means for locking the parts together by engagement of said spring and means for disengaging the spring to unlock the same, by continued movement in the locking direction only.

5. In a separable cuff button, two self-contained parts, a spring operable by movements of the parts toward each other to interlock the parts, and disengaging means

operable by movement in the locking direction only to laterally tension said spring to allow of separation of the parts.

6. In a separable button, two parts, means operable by movement of the parts toward each other to interlock them, means tending to hold the parts in locked position, and means acting in opposition to the locking means to radially tension the same to cause disengagement of the locking parts by parallel movement only of said parts.

7. In a separable cuff button, two parts, movable toward each other for locking them, a spring carried by one part, and means adapted to radially tension said spring and operable by movement in the same direction only to both lock the parts and to cause disengagement of the locking means.

8. In a separable button, two parts, a spring carried by the one part and normally in locking position, a stud with head carried by the other part, a sleeve carried by the said one part and having a slanting notch for cooperation with said spring, and a sleeve slideable on the stud to disengage the spring from its locking position.

9. In a separable button, two parts, movable toward each other for locking them, a spring carried by the one part and having flat portions, a sleeve carried by the said one part and having a slanting notch engaged by said spring, a stud and a ring movable on the stud to engage the said flat portions to move the spring out of the said notch.

In testimony whereof I affix my signature.
ERICK J. SWEDLUND.
